UNITED STATES PATENT OFFICE.

GEORGE S. GATCHELL, OF ROSELLE PARK, NEW JERSEY, ASSIGNOR TO THE SINGER MANUFACTURING COMPANY, A CORPORATION OF NEW JERSEY.

THREAD CONTROLLER.

Application filed January 2, 1919. Serial No. 269,225.

To all whom it may concern:

Be it known that I, GEORGE S. GATCHELL, a citizen of the United States, residing at Roselle Park, in the county of Union and State of New Jersey, have invented certain new and useful Improvements in Thread Controllers, of which the following is a specification, reference being had therein to the accompanying drawings.

10 This invention relates to a thread-controller for sewing machines.

It has for its object to provide an improved form of oscillatory thread-controller which will have all the advantages of the rotary form and in addition will avoid the winding of the thread around the take-up which is a common defect in the rotary forms. It also aims to secure greater compactness, thereby permitting the disposition 15 of the take-up in the work-arm of a cylinder bed machine without undue crowding or enlargement of the latter.

In its preferred form the improvement is embodied in a machine having an overhanging arm carrying a plurality of needles, and a cylinder-bed having mounted therein a common form of eyed looper and a feed mechanism, all of the moving parts being driven from a transversely disposed main-shaft, as in patent to Molyneux, No. 1,127,069, dated February 2, 1915. The take-up comprises a shaft mounted transversely in the cylinder-bed of the machine, said shaft being oscillated by an arm thereon connected 20 to an eccentric on the main-shaft. Secured to the shaft by set-screws are a take-up arm and a pull-off arm, a thread-nipper being disposed between them. The take-up and pull-off arms each have a slotted or bifurcated end through which passes a cast off arm. Pairs of thread guides are mounted on opposite sides of the take-up and pull-off arms to dispose the thread in the path 25 of said parts. The take-up arm is formed at its end with opposed, curved, thread-engaging surfaces, one of which is relatively extended and terminates in a hump or projection on the side of the arm, while the other surface merges with the first one at the top 30 of the arm and extends in a short sharp curve merging with the opposite side of the arm. The cast-off arm for the take-up has a concaved upper surface extending substantially horizontally at one end to coact 35 with the hump or projection, while the other

end curves sharply upward to form a projection coating with the sharply curved surface on the take-up. The pull-off arm has symmetrically opposed curved thread-engaging surfaces which merge at its end and 40 also merge with the sides of the arm. The cast-off arm for the pull-off has a concaved upper surface, one end of which coacts with one of the thread-engaging surfaces of the pull-off, and the other end of which concaved surface has a slight projection coacting 45 with the other thread-engaging surface of the pull-off. The pairs of thread-guides have pivotally mounted supports and are yieldingly held in either operative or inoperative position, and each support carries 50 a respective cast-off arm. Means are provided for adjusting the operative position of the thread-guides and cast-off arms relatively to their respective take-up and pull-off arms, which adjustment will vary the 55 amount of thread handled.

In the drawings, Fig. 1 is a side elevation of a sewing machine embodying my improved form of thread-controller, parts being broken away and omitted to more clearly disclose the controller and its operating mechanism. Fig. 2 is a top plan view of the controller, on an enlarged scale. Fig. 3 is a section through the work-arm or cylinder-bed, looking toward the controller. Fig. 4 is a section on the line 4—4, Fig. 2, but with the take-up and pull-off arms in the opposite position to that shown in Fig. 2. Fig. 5 is a section on the line 5—5, Fig. 2, but 60 with the parts also in the position opposite to that shown in Fig. 2.

Referring to the drawings, 1 indicates the standard of the machine, 2 the overhanging arm, 3 the needle-bar and 4 the needles. A cylinder-bed or work-arm 5 extends from the standard 1, in which are mounted a thread-carrying looper 6 and a feed-dog (not shown). The looper may be of any preferred form, such as shown in patent to 65 Molyneux, No. 1,127,795, February 9, 1915, or in my copending application Serial No. 185,446, filed August 10, 1917. The looper is rocked by the shaft 7 and sidewise movement is communicated to it by a shaft 8, said 70 shafts, the feed-dog and needle-bar all being actuated from the main-shaft 9 in a manner well known in the art. A rock-shaft 10 is mounted transversely in the work-arm 5 by pivot screws 11 and a rock-arm 12 extends 75

downwardly from one end of said shaft. To the lower end of the arm 12 is pivotally connected an arm 13 carried by an eccentric strap 14 surrounding an eccentric 15 mounted on the main-shaft 9. Secured to shaft 10 by a set-screw 16 is a take-up arm 17. The arm 17 is slotted as shown at 18 (Fig. 3) to provide for a cast-off member to be herein-after described. The top of the arm is provided with opposed cam surfaces which merge to form a continuous curve. The forwardly directed convex cam surface edge 19 (Fig. 5) extends inwardly or toward the center of the shaft 10 in a long, gradual curve up to the projection 20 at the front edge of the arm 17, which front edge is concaved inwardly of the projection 20. The rearwardly directed cam-edge 21 is relatively short and curved sharply downward from the point where it meets the surface 19 until it merges in the convex rear edge of the arm. Projecting upwardly from the inner bottom wall of the work-arm is a lug 22, and a bracket 23 is secured to said lug by a screw 24 passing through a slot 25 in the bracket and threaded into the lug. A block 26 is secured to the rear side of the bracket 23 by a screw 27, and a plate 28 (Figs. 2 and 5) is pivoted at its rear end to the block by a pivot pin 29. Extending forwardly from the plate 28 at each side of the take-up arm 17 are guide-arms 30 and 31 provided with thread-eyes 32. The plate 28 has a beveled portion 33 at its rear end (Fig. 5) in engagement with a flat spring 34. It will be noted that when the guide-arms are in lowered position the beveled portion 33 engages the spring 34 at one side of a bend 35 therein, while when the guide-arms are raised the portion 33 engages the spring on the other side of the bend, the guide-arms being thus yieldingly held in either position. The shank 36 of a cast-off arm 37 is secured to the plate 28 by a screw 38. The arm 37 has a cast-off portion 39 which is sharply inclined upwardly and is located in rear of the thread-eyes 32, which portion acts to cast off the thread from the rear cam surface 21 of the take-up arm as the latter moves rearwardly. The front portion 40 of the cast-off arm extends substantially horizontally but its upper surface curves slightly upward in a forward direction, and this portion acts to cast off the thread from the projection 20, as the take-up arm moves forwardly. An adjusting screw 41 (Fig. 2) is threaded through plate 28 and is adapted to engage the upper surface of the block 26 to vary the positions of the guide-arms and cast off arm relatively to the take-up arm.

Also mounted on the rock-shaft 10 is a pull-off arm 42 which is secured thereon by a set-screw 43. This arm is slotted at 44 to provide for a cast-off member to be herein-after described. The top of the arm is pro-

vided with opposite cam surfaces 45 of similar curvature which merge at their upper ends to form a continuous curve, while their lower ends merge into the side walls of the arm.

A second plate 46 is mounted on the block 26 alongside the plate 28 (Figs. 2 and 4) and is pivoted to the block at its rear end by the pin 29. Guide-arms 47 and 48 extend forwardly from the plate 46 on each side of the pull-off arm and are provided with thread-eyes 49 in alignment with the eyes 32. The plate 46 has a beveled portion 50 at its rear end in engagement with a flat spring 51 having a bent portion 52, by which the plate 46 and its guide-arms may be yieldingly held in raised or lowered position in a manner similar to the plate 28 and guide-arms 30 and 31. The shank 53 of a cast-off arm 54 is secured to the plate 46 by a screw 55, said arm having a concaved upper surface 54' adapted to engage with either side of the pull-off arm as the latter is oscillated, this concaved surface being slightly raised at its rear end to form a projection 54'' which aids in casting off the thread. An adjusting screw 56 is threaded through the plate 46 and is adapted to engage the upper surface of the block 26 to vary the position of the guide-arms 47 and 48 and the cast-off arm 54 relatively to the pull-off arm.

An arm 57 extends forwardly from the upper end of bracket 23 (Fig. 4) and has a vertical extension 58 located between the take-up and pull-off arms, said extension forming one member of a thread-nipper. The other member of the nipper is constituted by a flat spring 59 secured by a screw 60 to the front portion of the bracket 23, the upper end of the spring normally pressing against the extension 58 to nip the thread. A four cornered cam member 61 having slightly convexed sides is secured on the shaft 10 between the take-up and pull-off arms and is adjustably held by a set-screw 62, said cam member when the take-up is in its extreme rearward position as shown in Fig. 4 having one of its corners 61' bearing against the spring 59 to thereby open the nipper. It is evident from Fig. 4 that when the take-up is in extreme advanced position another corner will bear against the spring 59, again opening the nipper. In intermediate positions of the take-up and pull-off the nipper is closed. The looper-thread 63 leads from the supply through a tension 64 on the overhanging arm, then through the guide aperture 65 in the work-arm, through the eyes 49 in the guide-arms 48 and 47, between the nipper elements 58 and 59, through the guide-eyes 32 in the guide-arms 31 and 30, to the forward part of the work-arm and to the heel of the looper.

The operation of the take-up is as follows:—

When the parts are in the position shown in Fig. 1 the needles are all the way down, 5 the looper fully retracted, the take-up and pull-off advanced to their greatest extent and the nipper open. As the needles start up to throw out their loops the looper begins to advance, the nipper closes, and the 10 take-up and pull-off start rearwardly. Only a small take-up of thread is necessary at this time, due to the slack formed in front of the looper-eye, and the sharply inclined portion 39 quickly casts off the thread from the convexly curved cam surface 21 of the take-up, thereby effecting the desired result. As the 15 looper advances well into the needle-loops the thread is doubled along it and a relatively large supply of thread is necessary. 20 This is furnished by the thread slipping over the convex cam surface 19 and also by the opening of the nipper as the parts reach the position shown in Figs. 4 and 5. When this position is reached the needles 25 are all the way up, the looper fully advanced, the take-up and pull-off in their rear-most position, and the nipper opened. As the needles start down again, the looper is retracted, the nipper closes, and the take-up and pull-off start forwardly. It is evident 30 that on account of the doubling of the thread along the looper a large take-up is necessary during the first part of the looper retracting movement, and this is effected by 35 the concaved cam-edge immediately under the projection 20, as owing to the substantially horizontal disposition of the cast-off portion 40 said portion does not cast the thread over the projection 20 until the arm 40 17 has swung forward a considerable distance. As the looper continues in its backward movement it is necessary to supply slack thread to a limited extent. This is furnished by the thread slipping over the 45 cam surface 19 and down the surface 21, thread also being drawn through the nipper as the latter opens when the take-up and pull-off reach their forward position.

Having thus set forth the nature of the 50 invention, what I claim herein is—

1. In a sewing machine, a thread-carrying implement, an oscillatory cam take-up therefor having alternately acting concave and convex cam-edge portions, means for oscillating said take-up thread-guiding means, and relatively stationary cast-off means constructed and arranged to coact with said cam-edge portions and thread-guiding means to cause a differential thread control upon 55 movement of the take-up in different directions as it is oscillated.

2. In a sewing machine, thread-carrying means, thread-guides, an oscillatory take-up member moving between said guides and 60 having opposed convex and concave cam

edges adapted to alternately act upon the thread for different periods, and relatively stationary cast-off means coacting with said cam edges.

3. In a sewing machine, a thread-carrying 70 implement, a shaft, means for oscillating the same, a take-up arm carried by said shaft, thread-guiding means at opposite sides of the take-up arm, a relatively stationary cast-off arm, means carried by said 75 last arm for causing a relatively quick cast-off of the thread in one of the oscillatory movements of said first arm, and said arm adapted to cause a delayed cast-off of the thread on movement of the first arm in the 80 opposite direction.

4. In a sewing machine, a thread-carrying looper, guide-arms having thread-eyes, a shaft, means for oscillating the same, a take-up member secured to said shaft between 85 said guide-arms, an extended curved cam surface at one side of said take-up member and terminating in a projection, a relatively short curved cam surface at the other side of said take-up member, and cast-off means 90 having a horizontal portion in front of said thread-eyes for coaction with said projection and a sharply inclined upwardly directed portion in rear of said thread-eyes for coaction 95 with said second cam surface.

5. In a sewing machine, a pivotally mounted support carrying a pair of eyed thread-guides, an oscillatory shaft extending transversely of and below said guides, a slotted arm secured to said shaft and movable between said guides, forwardly and rearwardly extending curved take-up surfaces at the top of said arm, said forwardly extending surface terminating in a projection, a cast-off member extending through the 105 slot in said arm and having a forwardly directed portion coacting with said projection and an upwardly directed portion coacting with the rearwardly extending curved surface, and a thread-nipper and pull-off 110 coacting with said take-up.

6. In a sewing machine, an overhanging arm and a work-arm, a needle and an eyed looper carried by said respective arms, a shaft extending transversely of said work-arm, means for oscillating said shaft, opposed thread-guides, a take-up arm carried by said shaft and having convex and concave opposed cam edges adapted on oscillation of the shaft to engage opposite sides of the 120 thread extending between said guides, and relatively stationary cast-off means for the thread.

7. A thread-controller comprising an oscillatory shaft having an arm secured thereto, means for supporting a thread in the path of said arm, said arm having a concave cam-edge and lateral thread-engaging projection on one side thereof and an outwardly extending curved thread-engaging surface 130

extending from said projection across the free end of said arm and merging with its opposite side, and cast-off means disposed on opposite sides of said arm and coacting therewith to cause a differential thread control on oscillation of said shaft.

8. A thread-controller comprising an oscillatory shaft having slotted take-up and pull-off arms thereon, means for guiding a thread in the path of said arms, opposed cam surfaces on each of said arms for engaging the thread, one of the surfaces on the take-up arm being extended to form a thread-engaging projection, cast-off means extending through the slots in said arms and coacting with said surfaces, and a nipper located between said take-up and pull-off arms.

9. In a thread-controller, means for guiding the thread, an oscillatory shaft, a take-up carried by said shaft and having thread-engaging surfaces including a projection at

one side, a pull-off secured to said shaft and having opposed thread-engaging surfaces, and cast-off arms having concaved surfaces 25 coacting with the respective thread-engaging surfaces of the take-up and pull-off.

10. In a thread-controller, means for guiding the thread, an oscillatory shaft, a take-up carried by said shaft, cast-off means for 30 said take-up, a pull-off carried by said shaft and having opposed thread-engaging surfaces, and a cast-off for said pull-off having a concaved surface coacting with said thread-engaging surfaces as the pull-off is oscillated. 35

11. In a sewing machine, a thread-carrying implement, an oscillatory thread-take-up therefor having convex and concave thread-engaging cam-surfaces on opposite edges thereof, and means for oscillating said 40 take-up.

In testimony whereof, I have signed my name to this specification.

GEORGE S. GATCHELL.

Certificate of Correction.

It is hereby certified that in Letters Patent No. 1,432,683, granted October 17, 1922, upon the application of George S. Gatschell, of Roselle Park, New Jersey, for an improvement in "Thread Controllers," errors appear in the printed specification requiring correction as follows: Page 2, line 12, strike out the word "surface"; page 3, line 118, claim 6, before the word "convex" insert the word *opposed*, and line 119, strike out the word "opposed"; and that the said Letters Patent should be read with these corrections therein that the same may conform to the record of the case in the Patent Office.

Signed and sealed this 28th day of November, A. D., 1922.

[**SEAL.**]

KARL FENNING,

Acting Commissioner of Patents.
